MICROPHONE FOR SOUND DISPATCHING STATION

Joseph L. Bonanno, South Orange, N.J., assignor to The Lionel Corporation, New York, N.Y., a corporation of New York

Filed Dec. 9, 1957, Ser. No. 701,466
4 Claims. (Cl. 179—2)

This invention relates to model railways and more particularly to dispatching station control equipment therefor.

It is an object of the present invention to provide dispatching station equipment for model railways that will enable the operator to speak into a hand microphone for broadcasting over a built in speaker of a dispatching station.

Another object of the present invention is to provide a hand microphone having built in circuit control contacts for selectively controlling the movement of trains and the broadcasting of train information to a dispatching station.

Another object of the present invention is to provide a hand microphone of the above type having a novel contact plate supported therewithin for separately mounting the contacts of different control circuits in proper relationship for actuation by externally movable control members.

Other objects of the invention are to provide a hand microphone bearing the above objects in mind which is of simple construction, has a minimum number of parts, is inexpensive to manufacture and efficient in operation.

For other objects and for a better understanding of the invention, reference may be had to the following detailed description taken in conjunction with the accompanying drawings, in which:

FIGURE 1 is a top plan view, with the cover plate removed, of a control unit made in accordance with the present invention;

FIGURE 2 is a transverse cross sectional view taken along line 2—2 of FIGURE 1;

FIGURE 3 is a transverse cross sectional view taken along line 3—3 of FIGURE 1;

FIGURE 4 is an exploded perspective view of the electrical contacts forming a part of the present invention;

FIGURE 5 is a transverse cross sectional view taken along line 5—5 of FIGURE 1;

FIGURE 6 is a transverse cross sectional view taken along line 6—6 of FIGURE 1; and

FIGURE 7 is a transverse cross sectional view taken along line 7—7 of FIGURE 1.

In accordance with this invention, a hand control unit and portable microphone for model railways has been provided that is extremely authentic in appearance and effective for the purposes described.

Referring now more in detail to the drawing, a hand microphone 10 made in accordance with the present invention is shown to include a base member 12 defining a housing 13 that is adapted to receive and rigidly support a carbon granule type microphone unit 15. A cover plate 17 having grille work 18 is releasably secured, such as by bolts 51 extending through aligned bolt posts 50 to the base portion 12.

Within the handle portion of the unit 10, a switch or contact plate 20 is secured by means of a bolt 21. The outermost end of this switch plate or contact plate 20 is provided with a clamp 22 for securing the adjacent end of a wire conduit 24 thereto. A first set of contact plates 25, 26 are carried upon a perpendicularly extending mounting plate 28 of the bracket 20, insulated from each other and from the bracket by means of insulation 27, and secured in assembled relationship by means of rivets 29. Each of these contact plates 25, 26 at the opposite

2

end is provided with electric contact points 46, 47, respectively, which are in a normally closed circuit relationship. One pair of wires 23 are electrically connected to this first set of contact plates 25, 26. To another mounting plate 32 of the bracket 20, the contact plate 31 of another control circuit is connected by means of rivets 34 and insulation 33. The other set of wires 30 is connected, one to the contact plate 31 and the other to the terminal plate 36 of the bracket 20. A spring 37 is electrically connected to the terminal plate 36 at one end to a contact 38 on the microphone 15 on the opposite end. A contact point 42 carried at the outer end of the contact plate 31 is in a normally circuit open relationship with the conductor rim of the microphone 15 for reciprocating movement into and out of circuit closed relationship therewith to energize the microphone circuit.

A pair of manually operable pressure buttons 40, 44 are slidably supported at opposite sides of the unit for reciprocating movement into and out of the housing for actuating the respective control contacts. One button 40 controls the movement of the contact point 42 of the contact bar 31 into circuit closed engagement with the microphone 15, such button 40 normally being contained in the circuit open position by the spring action of the bar or plate 31. The other button 44 is associated with the terminal free end of the main plate 25 of the other set of contacts for movement toward a yieldable cushion 48. In response to the exertion of additional pressure against the cushion 48, the button 44 will flex the main terminal plate 25 a greater amount than the normal return movement of the smaller plate 26 so as to urge the contact point 46 out of engagement with the associated contact point 47 to open the control circuit through the wires 23. The opening and closing of these contacts is sufficient to control the starting, stopping, and reversing of the model railway locomotive motors, as is well known to those skilled in the art.

In accordance with the invention, the microphone 15 is of inexpensive but highly efficient construction, particularly adapted for a toy railroad. It includes a molded substantially dish-shaped housing 52 of plastic, or similar material, provided with a central elliptical cavity 53 which is filled with the usual sound actuatable material such as carbon granules 54. The cavity 53 is sealed at one end by a removable press-fit fill plug 56. An annular conducting member 58 is positioned around the cavity 53 and is provided with an extending portion 60 which extends outwardly through an aperture in the molded housing 52 and forms a portion of the contact 38.

The housing 52 is filled with pads of acoustic dampening material 62 which extend into contact with laterally extending portions 64 of the carbon granules. The carbon granules are retained in the cavity by a semi-elliptical insulated cover or cap member 66. A frustoconical diaphragm 68, a portion of the acoustic material 62, and the laterally extending portions of the granules 54 are covered by an intermediate conducting element 70. The intermediate conducting element 70 is anchored to the lower periphery of the cap 66 beneath and in contact with an inner annular portion 72 of the diaphragm 68. The diaphragm 68 also has an outer annular portion 74 which is maintained in contact with the acoustic material 62. A conductive cover plate 78 having annular side rims 80 is positioned on the housing 52 with the rims extending around the housing ends, to clamp the cover and the diaphragm 68 in position. The diaphragm 68 has a very small hole therein, at the portion 74, coupling the acoustic material chamber and the cavity between the cover plate 78 and the diaphragm. The side rim 80 is engaged by the contact 42 when the control button 40 is pushed through a microphone energizing position. Sound acting on the

diaphragm 68, when the latter is energized through the contact 42 and the rim 80, transmits the vibration through the granules 54 to the conducting element 58 in the form of electrical impulses.

In actual use, it is only necessary to depress the one button 40 to close the circuit through the carbon granule microphone 15 to permit the voice of the operator to be broadcast through an associated speaker. On the other hand, the other button 44 may be simultaneously or independently depressed to control the movement of the model railway train located on the associated trackway. It will be noted that all of the parts of the present device are readily accessible for repair and replacement purposes, whereby a compact and efficient hand control unit for model railways has been provided.

While the various changes may be made in the detail construction, it shall be understood that such changes shall be within the spirit and scope of the present invention as defined by the appended claims.

What I claim as new and desire to protect by Letters Patent of the United States is:

1. In a combination microphone and toy railway control unit for model railway trains including, a control circuit for operating trains on a power track and a microphone control circuit for connecting said microphone to an electrical current supply, the improvement comprising a housing having a hollow hand grip portion and an enlarged hollow microphone receiving portion, said control circuit including a fixed contact member and a resilient contact member normally in engagement therewith for closing said control circuit, said microphone control circuit including a microphone conductive rim contact portion and a resilient contact member in normally open relation with said rim contact portion, control circuit reciprocable button means biased in an outward direction by said control circuit resilient contact member, microphone control circuit reciprocable button means biased in an outward direction by said microphone control circuit resilient contact member, said first mentioned button means being manually actuatable in an inward direction to open said train operating control circuit and said second mentioned button means being manually actuatable in an inward direction to close said microphone operating control circuit.

2. Apparatus according to claim 1, wherein said control circuit reciprocable button means and said microphone control circuit button means are in axial alignment

and are located on opposite sides of said housing hollow hand grip portion.

3. Apparatus according to claim 1, including a contact support bracket having a pair of bent tab portions, and electrical isolating support means securing said control circuit fixed contact member and said control circuit resilient contact member to one of said tab portions and securing said microphone control circuit resilient contact to said other tab portion.

4. A hand microphone assembly for a toy railway dispatching station comprising, a housing having a hollow hand grip portion and an enlarged hollow microphone receiving portion, a microphone mounted within said receiving portion, said microphone including a container of sound actuatable variable resistance material, a first conductive element in contact with a portion of said sound actuatable variable resistance material, a conductive rim portion about said microphone electrically connected to said first conductive element, a second conductive element in contact with another portion of said sound actuatable variable resistance material, a resilient leaf spring contact fastened at one end to said housing and extending into said microphone receiving portion in proximity with said conductive rim portion, reciprocable button means for moving the other end of said leaf spring into contacting relation with said conductive rim portion, said resilient leaf spring contact biasing said reciprocable button means away from said rim portion into an unoperative position.
